BED DAVENPORT

Filed July 17, 1929

2 Sheets-Sheet 2

UNITED STATES PATENT OFFICE

RUDOLPH COOPERSMITH, OF ST. LOUIS, MISSOURI

BED DAVENPORT

Application filed July 17, 1929. Serial No. 378,860.

This invention relates to improvements in collapsible beds that may be opened or extended to form a full size bed or that may be closed or collapsed to form a davenport, couch, or equivalent elongated article of furniture for seating purposes.

Prior to the present invention, the bed bottom frame and associated mechanism had been secured to the outer frame of the davenport in such manner that access thereto for the purpose of repairs or other reasons was inconvenient and awkward, and the bottom frame and the mechanism either had to be disassembled and assembled in the davenport frame, or, when such assembly and disassembly could be effected outside of the davenport, the installation of these parts in the davenport frame or their removal therefrom was difficult and inconvenient. Accordingly, an object of the present invention is the provision of a structure of this kind in which all parts shall be easily accessible and removable.

In prior bed davenports in which a pair of bed bottoms or frames were superposed in the frame or box of the davenport when closed, and in which the upper bottom was lifted out over the front of the box and set down on the floor in front of the davenport frame while the lower bottom was raised to the level of the opened upper bottom, an objectionable feature was that the seat of the closed davenport had to be unduly high to accommodate thereunder the superposed bed bottom frames, mattress, and associated mechanism, or that the bed was unduly low when open or extended. Accordingly, another object of the present invention is to obviate these disadvantages.

Another object of the present invention is the provision of a folding bed of this character in which the opened bed may be closed by folding the section of mattress on the front bottom frame over the section of mattress on the rear bottom frame, and lifting the front frame up and back over the front of the davenport and down thereinto in superposition to the also lowered rear frame, the entire operation being accomplished without interference of the front frame and

its legs with the folded mattress on the rear frame.

Another object of the present invention is the provision of a bed of this character in which the lifting of the rear frame is counterbalanced by the simultaneous descent of the front frame.

A further object of the invention is to provide a bed of this kind which will be stable in both its open and closed positions.

Other objects, advantages, and desirable features of the invention will appear in the course of the following description of an illustrative embodiment of the spirit thereof.

In the accompanying drawings forming part of this specification, in which like numbers of reference denote like parts wherever they occur,

Figure 1 is a plan view of the bed extended or open, the davenport frame being shown in horizontal section;

Figure 2 is an end elevation of the same, showing fragments of the davenport frame to exhibit the connection of the bed bottoms and mechanisms with the said frame;

Figure 3 is a similar view showing the closed position of the bed in full lines, and an intermediate position in broken-and-dotted lines;

Figure 4 is a fragmentary transverse sectional view taken on the line 4-4 in Figure 2;

Figure 5 is a fragmentary sectional view taken on the line 5-5 in Figure 4; and

Figure 6 is a fragmentary enlargement view showing details of the catch and associated parts for securing the bed bottom supports in the davenport frame.

Briefly described, the bed davenport comprises a davenport skeleton or outer frame 1, ordinarily formed of wood in the conventional manner, that supports and gives form to the upholstering material with which it is covered, a base frame 2 supported in the davenport frame 1 so as to be bodily removable therefrom, and a bed bottom formed of a pair of sections 3 and 4 connected to each other and to the base frame 2 by suitable mechanism whereby the sections 3 and 4 may be superposed in the frame 1 or extended in side-by-side relation to form a full-size open

55

100

bed. The base frame 2, bed bottom sections 3 and 4, and the said mechanism are preferably formed chiefly of angle iron and flat bar iron sections riveted or otherwise rigidly and 5 suitably secured together.

The base frame 2 comprises rear corner angle uprights 5, front corner angle uprights 6, a rear angle beam 7 connecting the lower ends of the rear uprights 5, flat bar beams 8 10 at respective ends of the davenport and connecting the upper ends of the front and rear uprights thereat, bars 9 depending from intermediate portions of the beams 8, respectively, and corner braces 10 obliquely disposed in a vertical plane so as to subtend the corners between the angle beam 7 and the rear uprights 5 and having their opposite ends secured to the beam 7 and the adjacent upright respectively. The front internal corners of 15 the davenport frame 1 are lined with upright angle bars 11, suitably secured to the frame 1 as by screws or bolts 12, as shown in Figure 4, and having riveted or otherwise suitably attached thereto in the lower end of the front 20 flanges 13 of said bars 11, the studs 14 projecting interiorly from said flanges and being preferably provided with heads 15 on their outer ends. The front flanges 16 of the uprights 6 are provided with notches 17 extending upwardly from their lower ends, said notches being adapted for receiving said studs 14. The rear portions of the beams 8 are bowed outwardly at 18 to engage the outer frame 1 thereat, said engaging portions 18 being provided with notches 19, extending upwardly from their lower edges and adapted to receive screws 20 that project interiorly from the frame 1 thereat. The base frame 2 is locked to the outer frame 1 by catches 21 25 that are pivoted at 22 to the inner sides of the bars 8 so that they may be swung into position for closing the lower ends of the notches 19 to lock the frames together, as shown in Figure 2, or into position for opening the lower ends of the notches 19, as shown in 30 Figure 6, thereby allowing base frame 2 to be lifted up out of outer or davenport frame 1. The catches 21 are preferably in the form of depending plates having notches 23 in one side thereof to receive the screws 20. The inner ends of screws 20 are preferably provided with wing nuts 24 that may be turned to clamp the catches 21 in locking or securing 35 positions.

55 The rear bed bottom frame 3 comprises right and left angle bars 25 and 26, respectively, rigidly connected together by rear angle bar 27 and front angle bar 28. The front bed bottom frame 4 comprises right 40 and left angle bars 29 and 30, respectively, rigidly connected together by rear angle bar 31 and front angle bar 32. Rear angle bar 31 is positioned a slight distance forward of the rear extremity of bars 29 and 30, and the horizontal flanges 33 of bars 29

and 30 are cut away at their rear extremities 70 to retract their rear edges 34 so that the frame 4 will clear the folded mattress 35 on frame 3 when these parts are in the position indicated by broken and dotted lines in Figure 3, which is the position of their closest approach to one another intermediate of the open and closed positions of the bed. Levers 36, pivoted at 37 to the lower ends of the depending brackets or hangers 9, comprise upwardly extending arms 38, having their upper extremities pivoted at 39 to the rear portions of angle bars 25 and 26, respectively, and depending arms 40, having their lower extremities pivoted at 41 to one end of contractile helical springs 42, the opposite end of which is pivoted at 43 to the lower end of the uprights 5. L-shaped arms 44 are pivoted at one end at 45 to the lower portion of the lateral flange 46 of the respective uprights 6; at their bends by pins 47 working in slots 48 in the front portion of the bars 25 and 26, respectively; and at their other extremities by pins 49 affixed to the bar 44 80 and working in slots 50 in the intermediate portions of the bars 29 and 30, respectively. Depending plates or hangers 51, rigidly secured to the anterior portions of the bars 29 and 30, have their lower ends pivoted at 52 85 to the upper ends of legs 53, the intermediate portions of which are pivoted at 54 to one extremity of respective links 55. The arms 44 are preferably provided with extensions 56 that incline forwardly from the pivots 49, and the forward extremities of these extensions 56 are pivoted at 57 to the other extremities of the links 55. The arms 44 are braced together by a rod 58 in juxtaposition to the pivots 45, the ends of the rod being squared as at 59 to fit into square openings 90 in the arms 44, and the extremities 60 of these squared ends being flattened against the outer sides of the arms 44 in rivet-like fashion to make a rigid joint through which torque will be transmitted to the rod 58 and therethrough to opposite lever 44, whereby both levers 44 are compelled to rotate together, as best shown in Figures 4 and 5. Plates 61 are rigidly secured to the outer sides of the bars 25 and 26 behind the slots 48. Levers 62 are pivoted at 63 to the beams 8 intermediary of the hangers 9 and uprights 6, and the upper extremities of these levers are pivoted at 64 to plates 65, rigidly secured 100 to the rear extremities of the bars 29 and 30, respectively. Helical springs 66 and 67 are pivoted at one end at 68 and 69, respectively, to the bowed portions 18 of the beams 8, and at the other end through the intermediary of links 70 to the pins or studs 71 and 72, respectively, rigidly secured to the arms 62 at points oppositely located from the pivots 63, so that the springs 66 contract while the springs 67 expand, and vice versa. The bars 25, 26, 27, and 28 of the rear frame 110

115

120

125

130

3 may, of course, be provided with apertures 73 to receive the cross supporting wires 74 of a bed spring 75, which may be of any suitable or conventional type, and is indicated symbolically by the broken-and-dotted lines in Figures 1, 2, and 3. A similar bed spring 76 may be likewise borne by the bars 29, 30, 31, and 32 of the front frame 4. A covering 77 of the usual type may be placed over the spring 76, the ends being secured to wooden blocks 78 and 79 secured to the undersides of the bars 31 and 32, respectively.

The construction of the bed having been fully described, its mode of operation will be readily understood. To close the bed from the open position exhibited by Figures 1 and 2, the portion of the mattress 35 lying on the front spring 76 is folded over the portion of the mattress lying on rear spring 75 and the front frame 4 is lifted by raising its component bar 79. The ascent of frame 4 lifts pivots 49, thereby rotating arms 44 counter-clockwise, as viewed in Figure 2, the frame 4, however, being maintained in a substantially horizontal position by the levers 62 through the pivots 64, the articulation preferably being such that the frame 4 is slightly inclined toward the rear during that phase of its movement indicated by broken-and-dotted lines in Figure 3. The counter-clockwise rotation of arms 44 shifts the front of rear frame 3 to the rear, rather than downwardly, at first, through the intermediation of pins 47, slot 48, and plates 61, whose lower anterior corner 80 engages arms 44 by reason of the contractile tendency of springs 42. By reason of the initially rearwardly inclined position of arms 38, however, the backward movement of the frame 3 is accompanied by the depression of the pivots 39 and the tilting of the frame 3 to depress its rear end so that the latter will clear and pass underneath the bottom of the davenport back support or cushion 81. It will be observed that the frames 3 and 4 are separated by an intervening space when they are in the open position exhibited in Figures 1 and 2, and that this horizontal spacing of the frames is increased during the initial portion of the closing movement by reason of the horizontal component of the lifting movement of frame 4 being less than the horizontal component of the simultaneous movement of frame 3. Moreover, at this stage, frame 4 is ascending, while the vertical component of the movement of the front end of frame 3 is practically nil. Each of these characteristics of the movements of the frames 3 and 4 is desirable as tending to prevent interference between the frame 4 and the folded mattress on the frame 3, especially at their points of closest approach, indicated in broken-and-dotted lines in Figure 3. As the closing movement continues, rear frame 3 is lowered while front frame 4 is shifted over the front

wall 82 of the davenport frame 1 and into position in the frame 1 directly over the rear frame 3, until the parts occupy the final closed positions indicated in full lines in Figure 3. In this position, rear frame 3 is maintained in horizontal position, counter-clockwise tilting being prevented by the engagement of the rear end of the frame 3 with the upper side of the horizontal flange 83 of bar 7 of frame 2, and clockwise tilting being prevented by reason of the engagement of the upper anterior corner 84 of plates 61 with the arms 44. Frame 4 is, also, maintained horizontally when in closed position by reason of the engagement of arms 62 with the upper ends 85 of hangers 9 simultaneously with the engagement of arms 44 with the upper anterior corner 84 of plates 61. The slots 48 and 50 allow slight shifting of the pivotal connections thereto to compensate for slight inaccuracies of construction, and, also, allow for variation of the distance between the pivots 39 and 47, and between the pivots 64 and 49, thereby permitting a more compact arrangement of the mechanism with less liability of interference of parts than if the levers or arms 38, 44, and 62 had to be constrained to movements and positions imposed by the necessity of maintaining unvarying and constant the said distances throughout the cycle of operations. When the bed is open, as in Figures 1 and 2, the engagement of lower corner 80 of plates 61 with arms 44 prevents frame 3 from being shifted too close to frame 4 under the impulsion of springs 42, and washers 86 on pivot pins 64 engage the upper edge of arms 44 to prevent counter-clockwise tilting of frame 4, thereby preventing further clockwise movement of arms 44 when the legs 53 rest on the floor 87. The bed is, therefore, stable in both its open and closed positions, the weight of the front frame bearing on the arms 44 and thereby preventing counter-clockwise rotation of said arms, thereby preventing rearward movement of pivot 47 and, consequently, the descent of the rear bottom frame 3. It will be observed that the interposition of the plates 51 between the legs 53 and bars 29 and 30 enables the pivot points 52 to be lowered so that shorter legs 53 may be employed and a lower position of the pivot point 54 obtained, thereby allowing the extension arms 56 and the links 55 to be located below the level of the mattress on the spring 76 when the bed is open; and, when the bed is being closed, to lift the legs 53 so that they cannot interfere with the front wall 82 of the outer frame 1. Moreover, the legs 53 will straddle the folded mattress 35 when the bed is being closed and while it is in closed position. It will, also, be observed that the bed can be easily opened, since both bed bottom sections 3 and 4 are not lifted up together in the outer frame 1; but, at the beginning of

70

75

80

85

90

95

100

105

110

115

120

125

130

the opening movement, only upper frame 4 is lifted while lower frame 3 is merely being tilted; then, front frame 4 is shifted forwardly over the front wall 82 of the frame 1 and descends to the floor on the outside of the davenport while the rear frame 3 ascends simultaneously, so that the weight of the front frame 4, in descending to open position on the floor counterbalances the weight of the rear frame that is ascending at the same time. The weight of the rear frame 3, moreover, is counterbalanced by the springs 42; and the weight of the front frame 4, when being lifted in its rear position, is counterbalanced by the force exerted by stretched spring 67, spring 66 being slack, and when being lifted in its front position is counterbalanced by the force exerted by the stretched spring 66, spring 67 then being slack. When the bed is closed, the usual cushion may be placed on the covering 77 on the upper spring 76, and the top of the cushion will not be unduly high because the spring 76 and frame 4 are lower when the bed is closed than they are when it is open. Furthermore, the frames 2, 3, and 4 and their connecting mechanism may be quickly and bodily removed from the outer davenport frame 1 by loosening the wing nuts 24, shifting catches 21 to open the lower ends of notches 19, and thence lifting frame 2 up out of frame 1. Repairs or inspection of the parts or their disconnection from the other parts of the structure may then be made more easily since they are no longer so difficult of access as they might be were it impossible to remove the frames 2, 3, and 4 from the davenport without first disorganizing the parts.

Having thus fully described this invention, I hereby reserve the benefit of all changes in form, arrangement, order or use of parts, as it is evident that many minor changes may be made therein without departing from the spirit of this invention or the scope of the following claims.

I claim:

1. In a bed davenport of the kind including a back support, a frame, a front and a rear bottom section, a pair of levers pivotally borne by the frame and pivoted to the rear of the front section, arm means pivotally borne by the frame at a fixed point and pivoted to the rear portion of said rear section, and arm means pivotally borne by the frame and pivoted to one point to the front portion of the rear section and at another point to a portion of said front section, said arm means cooperating with the first-named arm means to cause the rear end of said rear section to be depressed to permit the passage of the latter underneath the bottom of the back support of the davenport, the second-named arm means and the levers being so organized to incline the rear portion of the

front section upwardly to avoid engaging the lifted front end of the rear section.

2. In a bed davenport of the kind including a back support, a frame, a front and a rear bottom section, a pair of levers pivotally borne by the frame and pivoted to the rear of the front section, arm means pivotally borne by the frame and pivoted to the rear portion of said rear section, said arm means being inclined rearwardly when the sections are extended with relation to the frame, and means comprising a pair of L-shaped arms, one leg of each of said arms being pivoted to said frame, the other leg being pivotally connected to a portion of the front section, the elbow portion thereof being loosely pivoted to the front portion of the rear section, said L-

3. In a bed davenport of the kind including a back support, a frame, a front and a rear bottom section, lever means pivotally borne by the frame and pivoted to the rear of the front section, arm means pivotally borne by the frame at a fixed point and pivoted to the rear portion of said rear section, and arm means pivotally borne by the frame and pivoted to one point to the front section of the rear section and at another point to a portion of said front section, said arm means co-operating with the first named arm means to cause the rear end of said rear section to be depressed to permit the passage of the latter underneath the bottom of the back support of the davenport, the second-named arm means and the lever means being so organized to incline the rear portion of the front section upwardly to avoid engaging the lifted front end of the rear section, said rear bottom section having means for engaging said second-named arm means to limit the rearward shift of the latter.

4. In a bed davenport of the kind including a back support, a frame, a front and a rear bottom section, lever means pivotally borne by the frame and pivoted to the rear of the front section, arm means pivotally borne by the frame and pivoted to the rear portion of said rear section, said arm means being inclined rearwardly when the sections are extended with relation to the frame, and means comprising a pair of L-shaped arms, one leg of each of said arms being pivoted to said frame, the other leg being pivotally connected to a portion of the front section, the elbow portion thereof being loosely pivoted to the front portion of the rear section, said L-

- shaped arms co-operating with said arm means to shift said rear section rearwardly and to cause the rear end of said section to be depressed to permit the passage of the latter 5 underneath the bottom of the back support, said L-shaped arms and the lever means being so organized to incline the rear portion of the front section upwardly to avoid engaging the lifted front end of the rear section, 10 said rear bottom section having means for engaging said second-named leg of said L-shaped arms to limit the rearward shift of the latter.
5. In a bed davenport of the kind including a back support, a frame, a front and a rear bottom section, lever means pivotally borne by the frame and pivoted to the rear of the front section, arm means pivotally borne by the frame at a fixed point and pivoted to the rear portion of said rear section, and arm means pivotally borne by the frame and pivoted to one point to the front portion of the rear section and at another point to a portion of said front section, said arm 20 means co-operating with the first-named arm means to cause the rear end of said rear section to be depressed to permit the passage of the latter underneath the bottom of the back support of the davenport, the second-named arm means and the lever means being so organized to incline the rear portion of the front section upwardly to avoid engaging the lifted front end of the rear section, said lever means and frame being arranged so that the frame limits the rearward swing of the lever means, and said rear bottom section and said second-named arm means co-operating to limit the rearward shift of the latter. 25
6. In a bed davenport of the kind including a back support, a frame, a front and a rear bottom section, lever means pivotally borne by the frame and pivoted to the rear of the front section, arm means pivotally borne by the frame and pivoted to the rear portion of said rear section, said arm means being inclined rearwardly when the sections 30 are extended with relation to the frame, and means comprising a pair of L-shaped arms, one leg of each of said arms being pivoted to said frame, the other leg being pivotally connected to a portion of the front section, the elbow portion thereof being loosely pivoted to the front portion of the rear section, said L-shaped arms co-operating with said arm means to shift said rear section rearwardly and to cause the rear end of said section to be depressed to permit the passage of the latter underneath the bottom of the back support, said L-shaped arms and the lever means being so organized to incline the rear portion of the front section upwardly to avoid engaging the lifted front end of the rear section, said lever means and frame having co-operating conformations to limit the rearward swing of the lever means, and said rear bottom section and said second-named leg of said arm means having co-operating conformations to limit the rearward shift of the latter. 35
7. In a bed davenport of the kind including a back support, a frame, a front and a rear bottom section, lever means pivotally 40 borne by the frame and pivoted to the rear of the front section, arm means pivotally borne by the frame and pivoted to the rear portion of said rear section, said arm means being inclined rearwardly when the sections are extended with relation to the frame, and means comprising a pair of L-shaped arms, one leg of each of said arms being pivoted to said frame, the other leg being pivotally connected to a portion of the front section, the elbow portion thereof being loosely pivoted to the front portion of the rear section, said L-shaped arms co-operating with said arm means to shift said rear section rearwardly and to cause the rear end of said section to be depressed to permit the passage of the latter underneath the bottom of the back support, said L-shaped arms and the lever means being so organized to incline the rear portion of the front section upwardly to avoid engaging the lifted front end of the rear section, said lever means and frame having co-operating conformations to limit the rearward swing of the lever means, and said rear bottom section and said second-named leg of said arm means having co-operating conformations to limit the rearward shift of the latter. 45
8. In a bed davenport of the kind including a back support, a frame, a front and a rear bottom section, lever means pivotally borne by the frame and pivoted to the rear of the front section, arm means pivotally borne by the frame and pivoted to the rear portion of said rear section, and arm means pivotally borne by the frame and pivoted at one point to the front portion of the rear section and at another point to a portion of said front section, said lever means and frame having conformation co-operating to limit the rearward swing of the lever means, 50
9. In a bed davenport, a frame, a front, and a rear bottom section, lever means pivotally borne by the frame and pivoted to the rear of the front section, arm means pivotally borne by the frame and pivoted to the rear portion of said rear section, and arm means pivotally borne by the frame and pivoted at one point to the front portion of the rear section and at another point to a portion of said front section, said lever means and frame having conformation co-operating to limit the rearward swing of the lever means, 55
10. In a bed davenport of the kind including a back support, a frame, a front and a rear bottom section, lever means pivotally 60 borne by the frame and pivoted to the rear of the front section, arm means pivotally borne by the frame and pivoted to the rear portion of said rear section, and arm means pivotally borne by the frame and pivoted at one point to the front portion of the rear section and at another point to a portion of said front section, said lever means and frame having conformation co-operating to limit the rearward swing of the lever means, 65

and said rear bottom section and said second-named arm means having conformations co-operating to limit the rearward shift of the latter.

5 In testimony whereof I hereunto affix my signature.

RUDOLPH COOPERSMITH.
